ATTORNEY

WITNESS:

Gerald J. Hennessy

UNITED STATES PATENT OFFICE.

ROBERT A. WADE, OF JERSEY CITY, NEW JERSEY.

DETACHABLE HEEL TREAD FOR SHOES.

Application filed July 19, 1924, Serial No. 727,007. Renewed September 12, 1925.

To all whom it may concern:

Be it known that I, ROBERT A. WADE, a citizen of the United States, residing at Jersey City, in the county of Hudson and State of New Jersey, have invented new and useful Improvements in Detachable Heel Treads for Shoes, of which the following is a specification.

This invention relates to improvements in 10 shoe heels and has for an object the provision of a detachable shoe heel tread, means being provided whereby the tread may be quickly and securely attached to a heel in a manner to permit of its removal and the 15 substitution of a new tread.

Another object of the invention is the provision of means for associating the heel and tread whereby relative lateral or turning movement will be prevented, additional 20 means being provided for yieldingly holding the tread against longitudinal movement with respect to the heel.

With the above and other objects in view, the invention further includes the following 25 novel features and details of construction, to be hereinafter more fully described, illustrated in the accompanying drawings and pointed out in the appended claims.

In the drawings:—

30 Figure 1 is an elevation partly in section showing a heel constructed in accordance with the invention, the section being taken substantially on the line 1—1 of Figure 2.

Figure 2 is a bottom plan view of the heel 35 body.

Figure 3 is an inner face view of the tread.

Referring to the drawings in detail where- 40 in like characters of reference denote corre- sponding parts, the reference character 10 indicates the body of the heel which is pro- vided at its lower end with a socket 11, the latter having extending from its inner wall a substantially centrally arranged projec- 45 tion or plug 12. The outer walls of the plug 12 and the inner walls of the socket 11 are of an irregular shape and are spaced apart to provide a groove 13, while the walls of the socket and plug are covered by a 50 metallic plate 14. This plate is secured in place by means of a pin 15 which extends

longitudinally and centrally through the heel.

The plate 14 is slotted as indicated at 16 so as to provide spring tongues, the free 55 ends of which are offset as shown at 17 so as to provide inwardly curved extremities for the tongues.

The tread of the heel is indicated at 18 and this tread is provided with a plug 19 60 which is shaped to conform to the walls of the socket 11. The plug 19 is socketed as shown at 20 and this socket is shaped to conform to the walls of the plug 12. The plug 12 is covered by a plate 21 which is 65 shaped to conform to the walls of the plug and which extends into the socket 20 and provides a frictional engagement with the body of the heel, the shape of the plugs and sockets preventing relative lateral or turn- 70 ing movement between the body and tread. The plate 21 is provided with recesses 22 at the base of its plug, the said recesses providing a substantially annular groove whose walls are curved to conform to the curvature 75 of the offset ends of the tongues 17 so as to provide a longitudinal connection between the heel body and the tread to hold the latter in place. The plate 21 is held in place by means of a pin or rivet 23. 80

The walls of the socket 11 and the plug 12 are provided with longitudinally disposed spaced tapered ribs 24 which are received within similarly arranged grooves 25 pro- 85 vided in the walls of the plug 19 and its socket 20 so that an additional frictional engaging means is provided.

The invention is susceptible of various changes in its form, proportions and minor details of construction and the right is 90 herein reserved to make such changes as properly fall within the scope of the ap- pended claims.

Having described the invention what is claimed is:—

1. A heel structure comprising a heel body having an irregular-shaped socket therein, yieldable tongues located within the socket and conforming to the shape of the walls of the latter, inwardly offset extremities at the 100 free ends of the tongues, a tread for the heel and a plug carried by the tread and

conforming to the shape of the tongues, therein, a tread for the body, an irregular-shaped tapered plug extending from one ¹⁰ face of the tread for frictional engagement with the walls of said socket and longitudinally disposed tapered interlocking ribs and grooves spaced around the plug and socket.

5 coacting with the tongues to hold the tread against turning with respect to the body.

2. A heel structure comprising a heel body having an irregular-shaped tapered socket

In testimony whereof I affix my signature.

ROBERT A. WADE.
